(57) **CLAIM**

The ornamental design for a compliance monitor for dry powder inhaler, as shown and described.

DESCRIPTION

FIG. 1 is a top plan view of a compliance monitor for dry powder inhaler according to our new design;

FIG. 2 is a left side elevation view of the invention of FIG. 1;

FIG. 3 is a front elevation view of the invention of FIG. 1; FIG. 4 is a right side elevation view of the invention of FIG. 1;

FIG. 5 is a rear elevation view of the invention of FIG. 1; FIG. 6 is a bottom plan view of the invention of FIG. 1; and FIG. 7 is a perspective view of the invention of FIG. 1 shown attached to a dry powder inhaler.

The broken lines shown in the figures depict portions of the compliance monitor for dry powder inhaler that form no part of the claimed design. The broken lines showing the dry powder inhaler are for illustration purposes only and form no part of the claimed design.
